United States Patent

Des. 235,113
Patented May 13, 1975

235,113

MOTOR GRADER VEHICLE

Vergil P. Hendrickson, Harold M. Johnson, Virgil H. Johnson, and Paul C. Rosenberger, Decatur, Ill., assignors to Caterpillar Tractor Co., Peoria, Ill.

Filed Apr. 30, 1973, Ser. No. 355,543

Term of patent 14 years

Int. Cl. D15—04

U.S. Cl. D40—5

Fig.-3-

Fig.-4-

FIG. 1 is a right side elevational view of a motor grader vehicle embodying our new design.

FIG. 2 is a left side elevational view thereof.

FIG. 3 is a front elevational view thereof.

FIG. 4 is a rear elevational view thereof.

FIG. 5 is a top plan view thereof.

We claim:

The ornamental design for a motor grader vehicle, substantially as shown.
